United States Patent Office

Des. 195,376
Patented June 4, 1963

195,376

COMBINED MUG AND COVER THEREFOR

William M. Curtis, Painted Post, N.Y., assignor to Corning Glass Works, Corning, N.Y., a corporation of New York

Filed Sept. 7, 1961, Ser. No. 66,637

Term of patent 14 years

(Cl. D58—17)

FIG. 1 is a side elevational view of a combined mug and cover therefor embodying my new design.

FIG. 2 is an exploded view of the same.

FIG. 3 is a top plan view.

FIG. 4 is a sectional view taken on line 4—4 of FIG. 2. The undisclosed side is a mirror image of the side shown.

I claim:

The ornamental design for a combined mug and cover therefor, as shown and described.
